UNITED STATES PATENT OFFICE.

CYRA B. WATTLES, OF PROVIDENCE, RHODE ISLAND, ASSIGNOR TO SURFACING MACHINE COMPANY, OF PROVIDENCE, RHODE ISLAND, A CORPORATION OF RHODE ISLAND.

FLEXIBLE SUPPORT FOR ABRASIVE MATERIALS.

No. 926,524.

Specification of Letters Patent.

Patented June 29, 1909.

Application filed November 11, 1905. Serial No. 236,917.

To all whom it may concern:

Be it known that I, CYRA B. WATTLES, a citizen of the United States, residing at Providence, in the county of Providence and State of Rhode Island, have invented a new and useful Improvement in Flexible Supports for Abrasive Materials, of which the following is a specification.

This invention has reference to an improvement in flexible supports on the face of which is secured an abrasive material such as sand, emery, corundum or similar abrasive or polishing substances.

The object of my invention is to improve the construction of a flexible support for abrasive materials whereby the flexible support may be detachably secured to the peripheral face of a grinding wheel or roll.

A further object of my invention is to prevent side movement of the flexible support on the face of the wheel or roll and I accomplish this object by forming on the back of the flexible support one or more raised surfaces in the form of thin ribs or lugs adapted to enter grooves or depressions in the face of the wheel or roll.

My invention consists in the peculiar and novel construction of a flexible support for abrasive materials, whereby the flexible support is firmly secured to the peripheral face of a grinding wheel or roll against circumferential or side movement caused by the abrasive surface of the flexible support coming into contact with the work, as will be more fully set forth hereinafter.

Figure 1 is a perspective view of my improved flexible support, showing the face of the same covered with an abrasive material and the construction of the enlarged or thickened ends of the support. Fig. 2 is a perspective view looking at the back of the flexible support on which is a series of raised surfaces in the form of thin longitudinal ribs adapted to enter grooves in the peripheral face of a grinding wheel or roll. Fig. 3 is a perspective view looking at the back of a modified form of flexible support on which is a series of raised surfaces in the form of thin lugs adapted to enter depressions in the peripheral face of a grinding wheel or roll. Fig. 4 is a transverse sectional view taken on line 4-4 of Fig. 2 in which the support is made of paper or similar material and the ribs on the back formed integral with the

support. Fig. 5 is a transverse sectional view taken on line 5-5 of Fig. 3 in which the flexible support may be made of paper or cloth and the lugs secured to the back of the same. Fig. 6 is a transverse sectional view of a still further modified form in which the raised ribs or lugs are formed integral with a flexible backing which is secured to the back of the flexible support by cement or other means.

In the drawings, *a* indicates a sheet of thin flexible material forming the flexible support and having the face *a'* covered with an abrasive substance such as sand, emery or corundum, the back *a''* on which is a series of raised surfaces *a³* *a³* and the enlarged ends *a⁴* *a⁴*. The sheet of flexible material *a* may be of paper, cloth, leather or any strong flexible material and is covered on the face *a'* with an abrasive material in the usual way. The raised surfaces *a³* *a³* on the back *a''* *a''* may be in the form of thin longitudinal ribs, as shown in Fig. 2, or in the form of lugs, as shown in Fig. 3. These raised surfaces may be formed on the back integral with the sheet of flexible material, as shown in section in Fig. 4, or formed separate, as shown in Fig. 5, of the same material or of metal and secured to the back in any well known way. The enlarged ends *a⁴* *a⁴* may be formed on the material by first folding a strip of thin metal over the ends of the material, as shown in broken lines in Fig. 1, and then bending the fold over, as shown in full lines in Figs. 1 and 2, or the ends of the material may be formed into a roll and riveted through, as shown in Fig. 3.

In the use of my improved flexible supports for abrasive materials the raised surfaces *a³* *a³* on the back are adapted to enter grooves or depressions in the peripheral face of a wheel or roll and the enlarged ends *a⁴* *a⁴* are adapted to be mechanically secured in the wheel or roll through a slot or slots in the face of the same, thereby detachably securing the flexible support with the abrasive material to the wheel or roll, and by the use of my improved flexible supports with the abrasive materials, the same is firmly held on the peripheral face of the wheel or roll against circumferential or side movement when in use.

It is evident that the raised surfaces *a³* *a³* on the back could be of any number required

and have any configuration desired, without materially affecting the spirit of my invention.

Having thus described my invention, I claim as new and desire to secure by Letters Patent:—

1. A sheet of flexible material covered on its face with an abrasive substance and having enlarged or thickened ends and a series of raised surfaces on its back, whereby the material is detachably secured on the peripheral face of a grinding wheel or roll against circumferential or side movement on the wheel or roll.
2. A sheet of flexible material covered on its face with an abrasive substance and having enlarged or thickened ends formed by folding a strip of thin metal over the ends and then bending the folded strip over, and a series of raised surfaces on the back of the material, whereby the material is detachably

secured on the peripheral face of a grinding wheel or roll against circumferential or side movement on the wheel or roll.

3. A sheet of flexible material covered on its face with an abrasive substance and having enlarged or thickened ends and a series of raised surfaces on the back, formed by constructing the raised surfaces integral with a sheet backing and securing the backing to the back of the material, whereby the material is detachably secured to the peripheral face of a grinding wheel or roll against circumferential or side movement on the wheel or roll.

35

In testimony whereof I have signed my name to this specification in the presence of two subscribing witnesses.

CYRA B. WATTLES.
